(57) **CLAIM**

The ornamental design for a slat for an agricultural combine, as shown and described.

DESCRIPTION

FIG. 1 is a front perspective view of a slat for an agricultural combine according to an aspect of the present invention.

FIG. 2 is a front view thereof.

FIG. 3 is a rear view thereof.

FIG. 4 is a top view thereof.

FIG. 5 is a bottom view thereof.

FIG. 6 is a first end view thereof; and,

FIG. 7 is a second end view thereof.

The surface shading and broken lines shown in FIGS. 1-7 represent portions of the slat for an agricultural combine that form no part of the claimed design.
